UNITED STATES PATENT OFFICE.

EDWIN LLOYD AND ERNEST WILLIAM LOWRY, OF LONDON, ENGLAND, ASSIGNEES TO
CANDLE-LEETE, LIMITED, OF LONDON, ENGLAND.

LAMP.

1,403,089.

Specification of Letters Patent. Patented Jan. 10, 1922.

Application filed April 11, 1921. Serial No. 460,599.

To all whom it may concern:

Be it known that we, EDWIN LLOYD and ERNEST WILLIAM LOWRY, both of 2 Basinghall Avenue, London, E. C. 2, England, both subjects of the King of Great Britain and Ireland, have invented certain new and useful Improvements in or Relating to Lamps, of which the following is a specification.

This invention relates to lamps of the type in which oil is placed in a container filled with absorbent material and a wick extends through an orifice in the container.

The object of this invention is to provide an improved lamp of this type.

15 A lamp made in accordance with this invention is provided with a wick holder within the container, a removable cap provided with a nozzle through which the wick extends and a nozzle guard to direct the air currents about the flame. The cap is also provided with a hole through which a pin or the like can be inserted for adjusting the wick and with or without means for fixing the lamp in a candle stick or in the ground, 25 and with or without a wind screen.

Referring to the drawings filed here-with:—

Fig. 1 is a sectional elevation of one form of lamp made in accordance with this invention which is constructed for use in the place of candles.

Fig. 2 is a modified construction for use in camps or mines showing means for fixing the lamp into the ground.

35 *a* is the container, *b* absorbent material, *c* is the wick holder mounted on a disc *d* having ears *e* by which it is soldered to the container, a coned cap *f* is adapted to fit on the container; the cap is provided with a nozzle 40 *g* and a nozzle guard *h* at the orifice of the nozzle. The nozzle guard is provided with a plurality of cuts *j* to direct the air on to the flame. A wind guard *k* protects the flame in a draught. The base of the container may 45 be provided with clips *m* to fit into the socket of a candle stick or with a spike *n* to fit into the ground. An adjusting hole *o* is formed in the cap through which a pin is inserted to adjust the height of the wick. A lamp so 50 constructed is well adapted for domestic use or for in mines or other purposes.

The screen may be made of metal, glass,

mica or other suitable substances, and may be colored if desired. In some cases a globe or chimney may be mounted on the cap or 55 container. The wick holder extends into the cap, the adjusting hole in the cap being above the top of the holder *c*.

In use the cap is removed, the container is filled with oil from the top so that the absorbent material is saturated; surplus oil may be poured off and the cap replaced; the lamp may be held in any position without spilling the oil.

This invention is not restricted to lamps 60 of candle form as shown in the drawings but may be applied to any form of oil lamps with any form of container.

What we claim and desire to secure by Letters Patent is:—

70 1. An oil lamp comprising a container, absorbent material within said container, a wick extending from said container, a removable cap on said container, a nozzle on said removable cap through which the wick 75 extends, a nozzle guard disposed around said nozzle, a wick holder disposed on the container, and a wind guard disposed on the removable cap.

2. An oil lamp comprising a container, absorbent material within said container, a wick extending from said container, a removable cap on said container, a nozzle on said removable cap through which the wick extends, a nozzle guard disposed around said 80 nozzle, a wick holder disposed on the container, and a wind guard disposed on the removable cap, and means for supporting the lamp.

3. An oil lamp comprising a cylindrical 90 container, absorbent material within said container, a wick extending from said container, a cone shaped removable cap on said container, a nozzle on said removable cap through which the wick extends, a nozzle 95 guard disposed around said nozzle, a wick holder disposed on the container, a wind guard disposed on the removable cap, and means for supporting the lamp.

4. An oil lamp comprising a cylindrical 100 container, absorbent material within said container, a wick extending from said container, a cone shaped removable cap on said container, a nozzle on said removable cap

through which the wick extends, a nozzle
guard disposed around said nozzle, a wind
guard disposed on the removable cap, means
for supporting the lamp, and a wick holder
disposed on the container, said wick holder
comprising a cylindrical member adapted to
fit the wick, a flange on the cylindrical mem-

ber, and ears on the flange adapted to be fas-
tened to the container.

In testimony whereof we have signed our 10
names to this specification.

EDWIN LLOYD.

ERNEST WILLIAM LOWRY.
